5,414

UNITED STATES PATENT OFFICE.

JAMES L. JACKSON, OF NEW YORK, N. Y.

DESIGN FOR HARNESS-BRACKET.

Specification forming part of Design No. 5,414, dated December 12, 1871.

To all whom it may concern:

Be it known that I, JAMES L. JACKSON, of the city and State of New York, have invented or produced a new and original Design for a Harness-Bracket; and the following is declared to be a correct description of the same:

This design relates to the general shape and configuration of the bracket, and said bracket is made especially for the saddles of double harness.

In the drawing said bracket is shown by a perspective view.

The back plate, to set against the wall or other place of attachment, together with the ornamental center or name-plate, are shown at *a* and *b*, respectively, and are to be of the ornamental

shape represented. The portion *c*, upon which saddles or other articles of harness may be placed, stands out at right angles, or nearly so, to the back plate *a*, and is formed as an open-work plate, with rounded edges rising slightly above the plate *c*. The contour of this plate *c* is clearly represented in the drawing.

I claim—

The design of the harness-bracket, substantially as shown and described.

Signed by me this 13th day of July, A. D. 1871.

JAMES L. JACKSON.

Witnesses:

HAROLD SERRELL,
GEO. T. PINCKNEY.
